CLAIM

The ornamental design for an operating panel for elevator, as shown and described.

DESCRIPTION

FIG. 1 is a perspective view 1 of an operating panel for elevator, showing my new design;

FIG. 2 is a perspective view 2 thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a partially enlarged view taken along line 9-9 of FIG. 3;

FIG. 10 is a partially enlarged view taken along line 10-10 of FIG. 3;

FIG. 11 is an enlarged cross-sectional view thereof; taken along line 11-11 of FIG. 9, with the internal system omitted;

FIG. 12 is an enlarged cross-sectional view thereof; taken along line 12-12 of FIG. 10, with the internal system omitted; and,

FIG. 13 is a front view of the design shown in use.

The broken line showing of an elevator car in FIG. 9 is included for the purpose of illustrating portions of the "article" and forms no part of the claimed design.
